UNITED STATES PATENT OFFICE.

VICTOR BIRCH HARRISON, OF TORONTO, ONTARIO, CANADA.

SHARPENING DEVICE.

1,312,538.

Specification of Letters Patent.

Patented Aug. 12, 1919.

Application filed November 29, 1918. Serial No. 264,727.

To all whom it may concern:

Be it known that I, VICTOR BIRCH HARRISON, a subject of the King of Great Britain, and resident of 34 Yonge street, city of Toronto, county of York, Province of Ontario, in the Dominion of Canada, have invented certain new and useful Improvements in Sharpening Devices, of which the following is a specification.

- 10 The invention relates to improvements in sharpening devices as described in the present specification and shown in the accompanying drawings that form a part of the same.
- 15 The invention consists essentially of the novel construction and arrangement of parts whereby each side of a razor blade clamp is provided with a longitudinally arranged roller adapted to engage a sharpening stone
- 20 for guiding said blade in its course therewith during the sharpening operation.

The objects of the invention are to insure the proper sharpening of a safety razor blade without altering the degree of slant of the bevel, to prolong the life of safety razor blades, and generally to provide a sharpening device which will be inexpensive to manufacture, durable and efficient.

In the drawings Figure 1 is a perspective view of the device with a blade clamped therein.

Fig. 2 is a perspective view of the device open.

Fig. 3 is a detail of the slotted handle to which the clamping plate is hinged.

Fig. 4 is a cross sectional view through the device.

Fig. 5 is a detail of one end of the base plate showing the slot in which the roller is secured and also showing the stem on which the handles are secured.

Like numerals of reference indicate corresponding parts in the various figures.

Referring to the drawings the clamp consists of a base plate formed up from a piece of metal having a substantially rectangular central portion 1 provided with a flat inner face and a convexed outer face 3 and having reduced ends 4 projecting therefrom and threaded at their outer ends as at 4^a, and a plate 5 identical in construction to the central portion 1 of the base plate and fitting thereover to hold the razor blade therebetween.

55 The plate 5 is adjustably secured in position above the base plate by means of a lug

6 projecting from one end thereof into a slot 7 in the handle 8 and pivotally held therein by a pin 9 extending through said handle and said lug.

60 The plate 5 is locked to the base plate by means of a sleeve or handle 10, at its outer end threading over the threaded portion of the end 4 at its inner end being provided with a longitudinal slot 11 to accommodate 65 a lug 12 from the end of said plate 5 and being adapted on being rotated to cover said lug to effectually prevent movement of said plate in any direction.

70 The plates 1 and 5 are considerably longer and narrower than a safety razor blade so as to permit of said blade being locked between the plates with the edges to be sharpened projecting beyond said plates at each side.

75 The plates 1 and 5 are each provided with a central longitudinal slot 13 extending throughout the greater part of the length of said plates, said slots increasing slightly in width from the flat faces of said plate outwardly and having reduced end portions 80 14, each of said slots being adapted to accommodate a roller 15 having a bearing from each end thereof adapted to enter the respective reduced end portion 14 and to be secured therein by closing the outer edges 85 of said reduced portions thereover.

85 The thickness of the device from the outer edges of the rollers 15 is preferably such that when the blade is inserted and the device is laid in position on the stone the whole 90 surface of the bevel of said blade will engage the surface of said stone thus effectually preventing the alteration of the bevel and insuring a perfect cutting edge.

95 The base plate 1 is preferably provided on its inner face with circular bosses 17 spaced to correspond to the usual openings in safety razor blades and the plate 5 provided with corresponding openings so that said bosses will pass completely through the 100 blade and extend into the openings in the upper plate and hold the blade rigidly to its position.

105 18 are caps screwing over the outer ends of the portions 4.

110 In the operation of this invention the blade to be sharpened is placed on the base plate 1 with the openings thereof fitting over the bosses 17, the plate 5 is then closed over the blade with the lug 12 fitting the slot 11 in the handle 10 and said handle is rotated sufficiently to cover said lug and prevent

movement thereof. The device is then grasped by the handles and propelled over the stone or strap with the corresponding roller and blade edge engaging the surface 5 of said stone or strap. The corresponding side edges of the blade may be sharpened simultaneously by allowing the engagement of one edge with the stone during one stroke and on the back stroke simply turning the 10 device back on the opposite side of the same roller and allowing the other edge of the blade to engage the stone.

It will thus be seen that by the employment of this device no skill whatever is required in sharpening a blade as the proportions 15 of the device insure the absolute preservation of the bevel.

What I claim is:—

1. In a sharpening device, a base plate, 20 handles projecting from the ends of said base plate, a pivoted plate adapted to be locked over said base plate and forming therewith a blade clamp, and rollers longitudinally arranged in said plates and projecting from 25 the outer faces thereof.

2. In a sharpening device, a base plate having reduced ends forming handle supports, handles threading over said supports, a plate hingedly secured in one of said handles and adapted to be locked over said base plate by the other of said handles, and rollers arranged in longitudinal slots in the outer faces of said plates.

3. In a sharpening device, a pair of plates 35 having convexed outer faces and flat inner faces, pivoted means for securing together said plates at one end, means for locking together the other ends of said plates, rollers longitudinally arranged in slots in the 40 outer faces of said plates and adapted to be rotated through engagement with a sharpening element, and handles.

4. In a sharpening device, a substantially 45 rectangular base plate having a flat inner face and a convexed outer face, handle sup-

ports integral with said base plate and projecting from each end thereof, handles mounted on said supports, a clamping plate having a flat inner face and a convexed outer face, means for pivotally securing said clamping plate to one of said handles, means for locking said clamping plate to the other of said handles over said base plate and rollers mounted in longitudinal bearings in 50 said plates and projecting from the convexed faces of said plates.

5. In a sharpening device, a pair of plates having flat inner faces and convexed outer faces, one of said plates having reduced ends 55 forming handle supports, a handle threading over one of said supports and slotted longitudinally at its inner end to receive a lug from the other of said plates to adjustably connect said plates, a handle rotatably mounted on the other of said supports and 60 slotted to receive a lug from said other plate for locking said plates and rollers longitudinally mounted in slots in said plates and projecting from said convexed faces.

6. In a sharpening device, a pair of substantially rectangular plates having flat inner faces and convexed outer faces, said plates being greater in length and of less width than a safety razor blade and being adapted to be clamped thereover with the 70 side edges of said blade projecting therefrom, slots longitudinally arranged through said plates and tapering inwardly slightly from said convexed faces and having reduced end portions forming bearings, rollers operating in said slots and having their 75 axles loosely mounted in said reduced portions, and handles.

Signed at Toronto, Ont., this 4th day of November, 1918.

VICTOR BIRCH HARRISON.
